CLAIM

The ornamental design for set of mixing bowls and lid for a nut milk maker, as shown and described.

DESCRIPTION

FIG. 1 is a front perspective view of a set of mixing bowls and lid for a nut milk maker, in use condition, showing our new design;

FIG. 2 is a front side elevation view of FIG. 1.

FIG. 3 is a back side elevation view of FIG. 1.

FIG. 4 is a left side elevation view of FIG. 1.

FIG. 5 is a right side elevation view of FIG. 1.

FIG. 6 is a top plan view of FIG. 1.

FIG. 7 is a bottom plan view of FIG. 1.

FIG. 8 is a front perspective exploded view thereof;

FIG. 9 is a front side elevation view of FIG. 8.

FIG. 10 is a back side elevation view of FIG. 8.

FIG. 11 is a left side elevation view of FIG. 8.

FIG. 12 is a right side elevation view of FIG. 8.

FIG. 13 is a top plan view of FIG. 8; and,

FIG. 14 is a bottom plan view of FIG. 8.

The broken lines in the drawings depict portions of the set of mixing bowls and lid for a nut milk maker that form no part of the claimed design.

1 Claim, 14 Drawing Sheets
